(57) CLAIM

The ornamental design for a spikeless sole for golf shoe, as shown and described.

DESCRIPTION

FIG. 1 is a bottom perspective view of the shoe sole showing our new design;

FIG. 2 is a front elevational view thereof;

FIG. 3 is a rear elevational view thereof;

FIG. 4 is a right side elevational view thereof; and

FIG. 5 is a bottom plan view thereof;

FIG. 6 is a left side elevational view thereof; and,

FIG. 7 is a top plan view thereof.

The broken line showing of the upper portion of the shoe is for illustrative purposes only and forms no part of the claimed design.
